UNITED STATES PATENT OFFICE.

LEONARD A. TIRRILL, OF LYNN, MASSACHUSETTS, ASSIGNOR TO GENERAL ELECTRIC COMPANY, A CORPORATION OF NEW YORK.

BACK-GEARED MOTOR.

SPECIFICATION forming part of Letters Patent No. 787,482, dated April 18, 1905.

Application filed August 5, 1904. Serial No. 219,538.

To all whom it may concern:

Be it known that I, LEONARD A. TIRRILL, a citizen of the United States, residing at Lynn, in the county of Essex and State of Massachusetts, have invented certain new and useful Improvements in Back-Geared Motors, of which the following is a specification.

My present invention relates to means for mounting a back gear or counter-shaft on the frame of an electric motor.

The various features of novelty which characterize my invention are pointed out with particularity in the claims annexed to and forming a part of this specification. For a better understanding of my invention, however, reference may be had to the accompanying drawings and description, in which I have illustrated and described one embodiment of my invention.

Of the drawings, Figure 1 is an end elevation of an electric motor equipped with my invention, the back gear itself being removed.

Fig. 2 is an elevation of the adjustable member to which the back-gear-supporting shaft is secured. Fig. 3 is a partial section on the lines 3-3 of Fig. 1. Fig. 4 is a view similar to Fig. 1 with the back gear in place, and Fig. 5 is a plan view of the motor shown in Fig. 4.

Referring to the drawings, 1 represents the main frame or field-ring of an electric motor. The main frame 1 is provided with integrally-formed supporting-feet 2. To the ends of the frame 1 are secured end plates or members 3 and 4. The armature-shaft 5 of the motor is journaled in bosses or boxes 6 and 7, carried by the end plates 3 and 4, respectively.

One end plate 4 has formed in it concentric with the armature-shaft an annular groove or channel 8. The groove or channel is undercut to be T-shaped in cross-section having an inner portion 9 and an outer smaller portion 10, as clearly appears in Fig. 3. An arc-shaped supporting member 11, formed with an arc-shaped rib 12, is adjustably clamped against the end member 4 by bolts 13. The rib 12 is fitted to slide in the portion 10 of the channel 8. The inner ends of the bolts 13 are tapped into nuts 14, which slide in the annular recess 10. The nuts 14 comprise a portion 15, which

slides in the portion 9 of the groove 8, and a portion 16, which slides in the portion 10 of the channel 8. The nuts 14 may be inserted in the annular channel 8 through openings 17, formed in the bottom wall of the recess.

A part 18, extending integrally from the member 11, is slotted at 19 to receive one end of the shaft 20. The shaft 20 is formed with a collar 21, which bears against the frontside of the part 18. The inner end of the shaft 20 is threaded, and a nut 22 serves as means for clamping the shaft 20 to the part 18. A gear-wheel 23, pivotally mounted on the shaft 20, meshes with a gear 24, carried at the end of the armature-shaft 5. Usually the gear 24 is smaller than the gear 23. A driving member, 25, is secured in any suitable manner to the gear-wheel 23. A nut 26 serves to hold the gear-wheel 23 in place on the shaft 20. The sprocket-wheel 25 may drive a sprocket-chain 27.

By adjusting the shaft 20 toward and away from the armature-shaft 5 in the slot 19 in the part 18 the gears 23 and 24 may be accurately fitted together. This also allows of the use of different-size gear-wheels 23. The construction shown allows the shaft 20 and parts carried by it to be angularly adjusted about the armature-shaft 5 to accommodate different positions of the motor and work driven by it. Suitable means which I have not thought it necessary to illustrate may be employed to lubricate the shaft 20.

What I claim as new, and desire to secure by Letters Patent of the United States, is—

1. In an electric motor, an end plate or member formed with an undercut channel in it, an armature-shaft journaled in said plate, a counter-shaft, a supporting member therefor, said supporting member being adjustably secured in said channel, a gear-wheel mounted on the armature-shaft, and a gear carried by the adjustable shaft meshing with the first-mentioned gear-wheel.

2. In an electric motor, an end plate or member having an annular undercut channel formed in it, an armature-shaft journaled in said end plate and carrying a gear-wheel, a

counter-shaft, a gear-wheel carried thereby meshing with the gear-wheel on the armature-shaft, and means for adjustably securing said counter-shaft to the end plate, said means comprising a device engaging the walls of said undercut groove or channel.

3. In an electric motor, an end plate or head having an undercut channel or groove formed therein, an armature-shaft journaled in said end plate or head, a gear carried thereby, a counter-shaft adjustably clamped to said head by clamping means entering said undercut groove or channel, and a gear on said counter-shaft meshing with the gear on the armature-shaft.

4. In an electric motor, an end plate or head formed with an undercut channel in it, an armature-shaft journaled in said end plate or head, a gear carried by said armature-shaft, a counter-shaft-supporting member adjustably secured to said end plate or head by clamping means entering said undercut groove or channel, a counter-shaft and means for adjusting it relative to said supporting member, and a gear on said counter-shaft meshing with the gear on the armature-shaft.
